UNITED STATES PATENT OFFICE

DAVID I. HASKELL, OF BROOKLINE, MASSACHUSETTS

DESIGN FOR A SHOE

Application filed November 9, 1929. Serial No. 33,387. Term of patent 14 years.

To all whom it may concern:

Be it known that I, DAVID I. HASKELL, a citizen of the United States, residing at Brookline, in the county of Norfolk and State of Massachusetts, have invented a new, original, and ornamental Design for Shoes, of which the following is a specification, reference being had to the accompanying drawing, forming part thereof.

The figure is a perspective view of a shoe, showing my new design.

I claim:

The ornamental design for a shoe, as shown.

DAVID I. HASKELL.
